UNITED STATES PATENT OFFICE

172,588

AIRPLANE

Frank N. Fleming, Malibu, and Harold T. Luskin,
Los Angeles, Calif., assignors to Douglas Air-
craft Company, Inc., Santa Monica, Calif.

Application September 1, 1949, Serial No. 4,803

Term of patent 7 years

(Cl. D71—1)

To all whom it may concern:

Be it known that we, Frank N. Fleming and Harold T. Luskin, citizens of the United States and residents respectively of Malibu and Los Angeles, all in the county of Los Angeles and State of California, have invented a new, original, and ornamental Design for an Airplane, of which the following is a specification, reference being had to the accompanying drawings, forming a part thereof.

Figure 1 is a three-quarter front view or perspective of the airplane embodying our new design in diving attitude;

Figure 2 is a front elevation of the airplane;
Figure 3 is a side elevation of same;

Figure 4 is a top plan view of the craft; and Figure 5 is a bottom plan view of same.

We claim:

The ornamental design for an airplane, substantially as shown.
